Primary Examiner — Philip S Hyder*Assistant Examiner* — Cary M Robinson(74) *Attorney, Agent, or Firm* — Yee & Associates, P.C.(57) **CLAIM**

The ornamental design for for a display screen with graphical user interface, as shown and described.

DESCRIPTION

FIG. 1 is a front view of a display screen with graphical user interface;

FIG. 2 is another front view of the display screen with graphical user interface, shown with a different broken line disclosure; and,

FIG. 3 is a front view of the display screen with graphical user interface, shown with another different broken line disclosure.

The dual set of outermost broken lines illustrate a display screen. The broken line showing of text, numbers, icons and boxes illustrate portions of the graphical user interface. None of the broken lines form part of the claimed design.

1 Claim, 3 Drawing Sheets(56)
